NONSTANGLING SELF-ENERGIZING HEAD
FOR PUNCTURING CLOSURE DISKS

Scott E. Allen, Glen Ridge, N. J., and Ozro N. Wiswell, Los Angeles, Calif., assignors to C-O-Two Fire Equipment Company, Newark, N. J., a corporation of Delaware

Continuation of application Serial No. 349,150, March 22, 1929. This application March 4, 1935, Serial No. 9,346

41 Claims. (Cl. 169—11)

The present application is a continuation of our co-pending application Serial No. 349,150, filed March 22, 1929.

This invention relates to a device for releasing fluid from a container and the embodiment of the invention presented in this application is particularly adapted for releasing an extinguishing fluid from a container, it being understood, however, that the broader principles of the invention are not limited to the application or details herein set forth. Not only is the entire combination of the invention novel, but so far as we are informed certain parts comprising less than the whole are combinatively new.

15 In the art of extinguishing fires by the use of an extinguishing fluid such as CO₂, it is necessary to have a releasing device for the container, which contains the carbon dioxide gas, which is susceptible of quick and positive action, so that the 20 carbon dioxide gas may be delivered to the area of the fire as quickly as possible after the releasing device is actuated.

It is an object of this invention to provide a releasing device in which the opening through which 25 the gas passes from the container will be entirely opened when the device is operated, so that the carbon dioxide gas may escape as quickly as possible.

It sometimes occurs that the actuating force 30 of the releasing device will not entirely puncture the closure member for the container, or open the exhaust passage of the container, and for this reason the fluid will flow slowly from the container and not pass as quickly as desirable to the area 35 of the fire.

It is one of the objects of our invention to provide a releasing device for the general use specified, in which the pressure of the fluid released from the container is utilized to fully open the 40 exhaust passage of the container.

It is a further object of the invention to provide a releasing device in which the puncturing member is caused to operate by an operating member, and in which the released fluid is directed 45 against the operating member to assist in actuating it.

A still further object of the invention is to provide a releasing device of the character mentioned, in which a seal is formed around the puncturing member when it is in operated position, to prevent a leakage around said puncturing member.

A more specific object of the invention is to provide in connection with a container having an outlet opening normally closed by a penetrable closure member, a cutter slidably fitting the opening and a fluid actuated piston for operating the cutter to open the closure member.

60 It is another object of the invention to pro-

vide a releasing device, in which the puncturing member is moved by pressure, and in which the fluid released from the container is utilized to assist in the operation of the puncturing member. In combination with this structure, means 5 is provided for preventing the released fluid from reaching a point to assist in the operation of the puncturing member until the pressure of the released fluid exceeds the pressure which primarily operates the puncturing member.

Another object is to employ a tubular penetrating member constructed and arranged to cut a flap out of the closure member so that the flap will be forced outwardly by pressure of the fluid in the container but will remain integrally attached to the body of the closure member.

Another object is to provide safety means which will yield to abnormal pressure and prevent bursting of the closure member normally closing the main discharge port of the container.

A still further object is to provide a relatively small port controlled by said safety means whereby in case the safety means is caused to yield the recoil developed by the discharge through the small safety port will be maintained within 25 desirable safety limits.

It is an object of the invention to provide a means for conveniently replacing and refilling the containers.

A further object of the invention is to provide 30 with a battery of containers and a set of interconnected control means for releasing fluid from the containers, releasable connecting and supporting means for the containers whereby any of the containers may be individually removed and replaced without disturbing the rest of the battery.

Other objects and advantages of the invention will be pointed out in the ensuing description.

Referring to the drawings in which the invention is illustrated,

Fig. 1 is a view illustrating a typical application of devices embodying our invention.

Fig. 2 is a vertical central section through a form of the invention which includes a piston as 45 an operating member, showing the parts in the unactuated position.

Fig. 3 is a plan or transverse section taken on the line 3—3 of Fig. 2.

Fig. 4 is a section similar to Fig. 1, but showing parts of the releasing device in operated position.

Fig. 5 is a vertical central section through another form of our invention, which utilizes a diaphragm as an operating member, showing the 55 parts in the unactuated position.

Fig. 6 is a plan section taken on the line 6—6 of Fig. 5.

Fig. 7 is a section similar to Fig. 5, but showing 60

the second form of the releasing device in operated position.

Referring to the form of the invention illustrated in Figs. 2 to 4 inclusive, the numeral 11 designates a container, which is provided with a threaded projection 12. Formed through the threaded projection 12 is an outlet or exhaust opening 13 which is closed by a sealing disk or diaphragm 14. The diaphragm 14 is secured in place to close the exhaust opening 13 by means of a plug 16 screwed into a threaded counter bore or opening 17 at the outer end of the projection 12. A body 18 is attached to the projection to bear against a face 19 of the threaded projection 12. The attachment may be made by means of a union member 20, which is screwed onto the threads of the threaded projection 12.

The body 18 is provided with a central vertical cylindrical chamber 23, in which an operating member in the form of a piston 24 is arranged for reciprocating motion. Carried by the piston 24 is a releasing member or a puncturing member 26. The puncturing member 26 is threadedly supported in an opening 27 of the piston 24. The lower end of the puncturing member 26 extends into a hole 28 formed in the plug 16, which holds the closure member 14 in place. The lower end of the puncturing member 26 is beveled off or pitched as clearly shown in Fig. 2. The end edge 30 of the member 26 is sharpened to readily penetrate and cut the closure member 14. It is to be noted that the lower end of the member 26 is cut away or notched at its uppermost part forming a recessed shoulder 30a and that the parts of the device are proportioned so that the cut away or notched part of the puncturing member does not cut the closure member when the device is operated. Through the notching or cutting away of the cutting edge of the member 26 and through the proportioning of parts, the closure member is cut so that its center part forms a flap 14x (Fig. 4) that is bent about the shoulder 30a as an anvil and folded back into the opening in the member 26 by the pressure of the fluid released from the container, but is not cut away or made free to be carried into the apparatus by the flow of fluid. Formed vertically through the puncturing member 26 and the piston 24 is an outlet passage 32, which is connected by lateral openings 33 to the upper part of the chamber 23 above the piston. It is to be noted that the cutting edge 30 is sharpened toward and coincides with the periphery of the passage 32, so that when the sealing disk is punctured the surrounding metal of the disk will jam tightly against the body of the cutter, forming a seal. A further advantage of having the cutting edge substantially coincident with the inner periphery of the cutter is that the flap is not of larger diameter than said periphery and is bent back readily into the cutter by the pressure of the released fluid. Located in the outlet passage 32 is a check ball 34, which is normally retained against a seat 35 by means of gravity.

The upper part of the piston 24 has a stem 37 connected to it, which passes outward through an opening 38 of the body 18 and is provided with a handle 39 on the outer end thereof. The piston 24 is normally maintained at the top of its stroke by a spring 37a operating against the body 18 and the handle 39. Connected to the body 18 and in communication with the upper end of the chamber 23 are fluid pipes 40, 41 and 42.

The lower part of the piston 24 is provided with a valve member 43, which is adapted to engage a

seat 44 provided by the plug 16, when the parts of the device are in operated position, as shown in Fig. 4. To permit a free downward movement of the piston 24, vent openings 45 are formed in the lower part of the chamber 23 so that the pressure cannot be built up below the piston. 5

Communicating with the exhaust opening 13 is a filler opening 47 formed transversely in the container 11 and intersecting the exhaust opening 13. The filler opening 47 is closed at one end 10 by a diaphragm 48 secured in place by a plug 49 which has an axial opening 50 and which is screwed into a threaded opening 51 in the container 11. The other end of the filler opening 47 is closed by a filler valve consisting of a threaded body 52 threadedly secured into an opening 53 in the container. The body 52 is provided with an axial opening 54 providing a seat 55 for a ball valve 56 retained in the opening by a retainer 57. Arranged over the outer end of the body 52 is a 20 threaded cap 58.

This form of the invention may be operated manually or may be operated by a fluid pressure. When manually operated, the piston 24 is depressed by forcing downward on the handle 39. 25 The piston 24 and the puncturing member 26 move downward until the knife edge 30 of the puncturing member 26 penetrates the closure member 14. This will allow the fluid under pressure to escape from the container 11 through the 30 exhaust opening 13 and into the outlet passage 32. The pressure of the fluid will upset the check ball 34 and the fluid will pass into the upper part of the chamber 23. The pressure of the released fluid against the piston 24 will force it 35 downward into a fully operated position as shown in Fig. 4. In this position, the closure member 14 is completely punctured and the fluid may quickly pass from the container 11.

This fluid is carried from the chamber 23 40 through any of the pipes 40, 41 or 42. It will be seen that when the parts are in the position shown in Fig. 4, the valve 43 is in engagement with the seat 44, so that no fluid can leak around the puncturing member 26. 45

When the plunger is operated by a fluid pressure, the fluid pressure admitted through one of the pipes acts on the plunger and puncturing member to move them downward until the closure disk 14 is punctured. The fluid under pressure will pass through the exhaust opening 13 into the outlet passage 32, but will not unseat the check ball 34 until the pressure of the released fluid exceeds the pressure of the fluid which primarily actuates the plunger 24. When 55 the pressure of the released fluid exceeds that of the fluid which primarily actuates the plunger 24, the check ball 34 will be unseated and the released fluid will pass outward through one of the pipes 40, 41 or 42. 60

As a means for creating a fluid pressure against the piston 24 we may provide a means for supplying the fluid under pressure from another cylinder or we may provide other means for creating a fluid pressure, such for example 65 as an explosion plug shown in our application entitled Device for puncturing closure disk, Serial No. 208,717, filed July 27, 1927.

The form of our invention shown in Figs. 5 to 7 inclusive has a body 60, which is secured to 70 the threaded projection 12 by means of the union member 20. The body 60 includes a cover 61, which is attached thereto by means of machine screws 62.

The body 60 provides a chamber 63 in which 75

an operating member in the form of a diaphragm 64 is secured. This diaphragm 64 is secured between the lower part of the body 60 and the cover 61. Supported by the diaphragm 64 is a puncturing member 65, which is secured thereto by means of a nut 66, screwed on to a threaded portion 67 of the puncturing member 65 that projects upwardly through the center of the diaphragm. The puncturing member 65 has a flange 68 below the diaphragm 64 and the nut 66 has a flange 70 above the diaphragm 64. The flanges are tightly clasped against the diaphragm to prevent leakage. The lower end of the puncture member 65 extends into the opening 28 of the plug 16 and is provided with a knife edge 71 whereby the closure 14 may be punctured. An outlet passage 72 is provided vertically through the puncture member 65. The lower end of the passage 72 communicates with the lower end of the puncturing member and the upper end communicates with the chamber 63 by means of lateral openings 74 and the nut 66.

The puncturing member 65 is provided with a valve face 15, which engages the valve seat 16 when the parts are in operated position, as shown in Fig. 7. In order that the diaphragm 64 may readily move into operative position, the body 60 is provided with vent openings 11, which prevent a pressure from being built up in the member 60 below the diaphragm.

Attached to the cover 61 and in communication with the chamber 63 are pipes 18 and 19. A fluid under pressure may be delivered to the chamber 63 through either of these pipes 18 or 19. We wish to point out that other means for producing a fluid pressure in the chamber 63 may be provided.

63 may be provided.

In the operation of this form of the invention, a pressure is built up in the chamber 63, which moves the diaphragm and the puncturing member into the position shown in Fig. 7. The chamber 63, is, of course, open through the outlet passage 72, but by providing a close fit between the lower end of the puncturing member 65 and the opening 28 of the plug 16, the leakage will be very small. When the closure disk 14 is punctured the fluid under pressure will pass through the exhaust opening 13 of the container 11 and through the outlet passage 72 into the chamber 63, where the pressure thereof will be utilized to force the diaphragm 64 and the puncturing member 65 into completely operated position, as shown in Fig. 7. The released fluid may pass from the chamber 63 through either of the pipes 78 or 79. The engagement of the valve face 15 with the valve seat 16 prevents the released fluid from escaping around the puncturing member 75 and through the vent opening 17. It will be noted that the cutting edge of the puncturing member shown in Figs. 5 and 7 is also sharpened toward and coincides with the periphery of the passage 72, so that when the disk 14 is cut there will be a tight seal of the disk against the body of the cutter. This is indicated in Fig. 7 where the cut edge of lip 14' of the disk is cupped downwardly by the puncturing member and bears against the bevel of the cutting edge. The puncturing member cuts out a piece 14a from the disk 14 and this piece is blown by the fluid pressure through the puncturing member so that it lodges against the cap 66 as shown in Fig. 7.

The important feature of the present invention is the utilization of the pressure of the released fluid to move the puncturing member into com-

pletely operated position, so that it is assured that the closure member will be completely penetrated.

Referring to Fig. 1, we have shown a series of containers 11 fitted with the form of our device shown in Fig. 2. The containers are supported on blocks 81 which support them a distance from the floor for purposes that will appear hereinafter. The containers are maintained in an upright position by clamps 82 which grip the sides thereof. The head with the puncturing device, represented collectively by the numeral 83, is attached to the container 11. The outlet pipes 40, 41 and 42 from the heads are interconnected, the pipe 40 of one head 83 being connected to the pipe 41 of the adjoining head, and pipes 42 on all heads leading to a common header 84 with an outlet 85 connected to distributing devices.

To release the fluid in the containers it is only necessary to depress the handle 39 of any one of the heads 83. This releases the fluid in that container as explained heretofore and produces a fluid pressure in the pipes 40, 41, 42 and the header 84. The fluid pressure being transmitted through the pipes 40 and 41 produce a pressure in the upper portion of the chamber 23 and causes a puncturing of the diaphragm 14 and a release of the fluid in the container 11 as explained heretofore. This fluid then passes through the header 84 to its opening 85 and the distributing devices.

When it is desired to replace one of the containers 11 it is necessary to unscrew the union member 20, loosen the clamp 82, and remove the block 81. This permits the container 11 to be lowered the distance which it was supported above the floor. This distance is greater than the distance between the seat 44 and the face 19 of the head 83 and it therefore allows the seat 44 to clear the face of the body 18 which contacts the face 19. The cylinder can, therefore, be easily moved for recharging or replacing. It should be noted that we have made the distance between the seat 44 and the face 19 of the head 83 small so that the distance that the container 11 must be lowered for removal is small.

In recharging, the cap 58 is removed from the filler valve and the recharging means attached to the threaded body 52. The pressure exerted by the recharging fluid displaces the ball valve 56 from its seat 55 and allows the fluid to pass through the opening 47 to the opening 13 and thence to the interior of the container 11. The diaphragm 48 has a lower rupturing value than the diaphragm 14 so that in case of an excess pressure in the container 11 this diaphragm will rupture before the container or the diaphragm 14. This is of particular benefit where recharging is undertaken with the container attached to the head 63, and the rupturing of the diaphragm 14 would create a pressure in the other heads and operate them so as to release the pressure contained therein. The port 50 in the safety plug is considerably smaller in cross-section than the main discharge outlet 13 so as to prevent excessive recoil in case of a discharge through the safety port. This is of particular importance in portable cylinders or in cylinders that are not hooked up into a system and hence are not firmly anchored, because the discharge of the high pressure fluid through a large safety port would result in a powerful recoil that might do a great deal of damage. The cross-sectional area of the main discharge port must necessarily be large enough to permit free

and rapid discharge of the fluid, but the diameter of the safety port is preferably only large enough to insure escape of fluid fast enough to keep the pressure in the cylinder below a predetermined maximum under extreme temperature variations. The discharge from such relatively small opening will not develop sufficient recoil to cause any real harm.

In the drawings and in the foregoing description, we have presented two forms of the invention. We wish it to be understood that various modifications may be made in the device without departing from the spirit and scope of the invention. We, therefore, wish our invention to be construed wholly by the appended claims.

We claim as our invention:

1. A releasing device for use in connection with a fluid container having an opening, and a closure for the opening, comprising: a body forming a chamber; an operating member in said chamber; means whereby said operating member may be actuated; and a puncturing member associated with said operating member, said puncturing member being operable by said operating member to puncture said closure, there being means for utilizing the released fluid to assist in actuating said operating member.

2. A releasing device for use in connection with a fluid container having an opening, and a closure for the opening, comprising: a body forming a chamber; an operating member in said chamber; means whereby said operating member may be actuated; a puncturing member associated with said operating member, said puncturing member being operable by said operating member to puncture said closure, there being means for utilizing the released fluid to assist in actuating said operating member; and means for forming a seal around said puncturing member when said puncturing member is in operated position.

3. A releasing device for use in connection with a fluid container having an opening, and a closure for the opening, comprising: a body forming a chamber; an operating member in said chamber; means whereby said operating member may be actuated; a puncturing member associated with said operating member, said puncturing member being operable by said operating member to puncture said closure, there being an opening in said puncturing member located to receive released fluid and pass it to the chamber to assist in actuating said operating member.

4. A releasing device for use in connection with a fluid container having an opening and a closure for the opening, comprising: a body forming a chamber; an operating member in said chamber; means whereby said operating member may be actuated; a puncturing member associated with said operating member, said puncturing member being operable by said operating member to puncture said closure, there being an opening in said puncturing member receiving released fluid and conducting it to the chamber to assist in actuating said operating member; and means for forming a seal around said puncturing member when said puncturing member is in operated position.

5. A releasing device for use in connection with a fluid container having an opening, and a closure for the opening, comprising: a body forming a chamber; an operating member in said chamber; means whereby said operating member may be actuated; a puncturing member associated with said operating member, said

puncturing member being operable by said operating member to puncture said closure, there being means for conveying the released fluid to said chamber so that the pressure thereof may be utilized to assist in the actuation of said operating member; and check means for preventing said fluid from reaching said chamber until the pressure thereof exceeds the pressure in said chamber.

6. A releasing device for use in connection with a fluid container having an opening, and a closure for the opening, comprising: a body forming a chamber; an operating member in said chamber; means whereby said operating member may be actuated; a puncturing member operable by said operating member to puncture said closure, there being means for conveying the released fluid to said chamber so that the pressure thereof may be utilized to assist in the actuation of said operating member; check means for preventing said fluid from reaching said chamber until the pressure thereof exceeds the pressure in said chamber; and means for forming a seal around said puncturing member when said puncturing member is in operated position.

7. A releasing device for use in connection with a fluid container having an opening, and a closure for the opening, comprising: a body forming a chamber; an operating member in the form of a piston in said chamber; means whereby said operating member may be actuated; and a puncturing member associated with said operating member, said puncturing member being operable by said operating member to puncture said closure, there being means for utilizing the released fluid to assist in actuating said operating member.

8. A releasing device for use in connection with a fluid container having an opening, and a closure for the opening, comprising: a body forming a chamber; an operating member in the form of a piston in said chamber; means whereby said operating member may be actuated; a puncturing member associated with said operating member, said puncturing member being operable by said operating member to puncture said closure, there being means for utilizing the released fluid to assist in actuating said operating member; and means for forming a seal around said puncturing member when said puncturing member is in operated position.

9. A releasing device for use in connection with a fluid container having an opening, and a closure for the opening, comprising: a body forming a chamber; an operating member in the form of a piston in said chamber; means whereby said operating member may be actuated; a puncturing member associated with said operating member, said puncturing member being operable by said operating member to puncture said closure, there being an opening in said puncturing member receiving released fluid and passing it to the chamber to assist in actuating said operating member.

10. A releasing device for use in connection with a fluid container having an opening, and a closure for the opening, comprising: a body forming a chamber; an operating member in the form of a piston in said chamber; means whereby said operating member may be actuated; a puncturing member associated with said operating member, said puncturing member being operable by said operating member to puncture said closure, there being means for conveying

the released fluid to said chamber so that the pressure thereof may be utilized to assist in the actuation of said operating member; and check means for preventing said fluid from reaching

5 said chamber until the pressure thereof exceeds the pressure in said chamber.

11. A releasing device for use in connection with a fluid container having an opening, and a closure for the opening, comprising: a body 10 forming a chamber; an operating member in the form of a piston in said chamber; means whereby said operating member may be actuated; a puncturing member associated with said operating member, said puncturing member being operable by said operating member to puncture said closure, there being means for conveying the released fluid to said chamber so that the pressure thereof may be utilized to assist in the actuation of said operating member; check 15 means for preventing said fluid from reaching said chamber until the pressure thereof exceeds the pressure in said chamber; and means for forming a seal around said puncturing member when said puncturing member is in operated 20 position.

12. A releasing device for use in connection with a fluid container having an opening, and a closure for the opening, comprising: a body forming a chamber; an operating member in said 25 chamber; means whereby said operating member may be actuated; and a member for opening the closure associated with said operating member, said member being operable by said operating member to puncture said closure, there being 30 means for utilizing the released fluid to assist the first mentioned means in actuating said operating member.

13. A device for opening a fluid container including an opening member operable to open the 35 container, an actuating member for operating the opening member, means for operating the actuating member, and means whereby fluid released from the container acts with the first mentioned means on the actuating member to operate it.

14. A releasing device for use in connection with a fluid container having an opening, and a closure for the opening, comprising: a body forming a chamber; an operating member in said chamber; 40 means for actuating the operating member; and a puncturing member operable by said operating member to puncture said closure, there being means for utilizing the released fluid to assist in actuating said operating member in moving the 45 puncturing member.

15. A device for opening a fluid container including, an opening member, fluid pressure actuated means for operating the opening member, and a connection between the container and said 50 means allowing fluid released from the container to act on said means.

16. A device for opening a fluid container including, an opening member, fluid pressure actuated means for operating the opening member, a 55 connection between the container and said means allowing fluid released from the container to act on said means, and a control for said connection preventing fluid from the container from acting on said means until its pressure exceeds that actuating said means.

17. In combination, a plurality of control devices, means operatively interconnecting the control devices, a plurality of fluid containers to be controlled by said devices, means for detachably 60 connecting the control devices and containers

when the containers are positioned to cooperate with the devices and while the control devices are interconnected, and releasable supporting means for holding the containers in said position.

18. In combination, a unitary structure including, a plurality of control devices and means operatively interconnecting the control devices, a plurality of fluid containers to be controlled by said devices, means for detachably connecting the control devices and containers when the containers are positioned to cooperate with the devices and removable supporting means for holding the containers in said position, each device including means preventing escape of fluid when its container is detached. 15

19. The combination of a container, a delivery connection, a chambered coupling in communication with the container and the delivery connection, a sealing disk interposed between the container and the delivery connection, a piston 20 mounted in the chamber of the coupling and subject to pressure from an external source, means to prevent effective resistance to the operative movement of the piston, and a tubular cutter carried by the piston and communicating beyond the 25 piston with the chamber and adapted to rupture the disk in its forward movement with the piston.

20. In an apparatus of the character described, a container for a medium under pressure, a closure for retaining the medium in the container 30 including a frangible disk, means for rupturing the frangible disk at will to permit the release of the medium, a conduit for conducting the released medium to a desired point at which it is not desirable to have an accidental discharge of the fluid, and means for protecting the frangible disk against failure due to an increase in the pressure within the container, said means including a port not in communication with the conduit and closed by a second frangible disk designed 35 to burst at a pressure lower than that at which the first disk is designed to burst.

21. In combination, a plurality of control devices, means operatively interconnecting the control devices, a plurality of fluid containers to be 40 controlled by said devices, and means for detachably connecting the control devices and containers when the containers are positioned to cooperate with the devices, each control device including means preventing escape of fluid therefrom when its container is detached. 45

22. In combination, a plurality of control devices, means operatively interconnecting the control devices to form a unitary assembly, a plurality of fluid containers adapted to be elevated to 50 position to supply fluid to the control devices, means for detachably connecting the containers and control devices when the containers are positioned to supply fluid to the devices, and removable supports for individually holding the containers in position to supply fluid to the devices, each control device including means preventing escape of fluid therefrom when its container is detached. 55

23. In a control for a fluid container having an outlet passage, a frangible disk, means holding the disk in position to close said passage, a cylinder, a piston operable in the cylinder, a member carried by the piston to be operated thereby to open the disk, and a washer located to act between the piston and said means upon the piston being operated to actuate said member, said piston having a passageway therethrough for the escape of fluid from the container.

24. The combination of a container, a delivery connection, a chambered coupling in commun-

cation with the container and the delivery connection, a sealing disk interposed between the container and the delivery connection, a piston member mounted in the chamber of the coupling and subject to pressure by which it may be driven toward the disk, means to prevent effective resistance to the operative movement of the piston, a device carried by the piston and adapted to rupture the disk in its forward movement with the piston, and means to prevent communication between the container and the face of the piston opposite the face subjected to pressure, said device being tubular and affording a means of escape for fluid from the container.

15 25. The combination of a container, a delivery connection, a chambered coupling in communication with the container and the delivery connection, a sealing disc interposed between the container and the delivery connection, a piston mounted in the chamber of the coupling and subject to pressure by which it may be driven toward the disk and having a passage therethrough, and a device carried by the piston and adapted to rupture the disk in its forward movement with the piston, said passage providing communication between the container and the delivery connection when the disk is ruptured.

30 26. The combination of a container, a delivery connection, a chambered coupling in communication with the container and the delivery connection, a sealing disk interposed between the container and the delivery connection, a piston mounted in the chamber of the coupling and subject to pressure from an external source and having a sleeve extension above its head provided with a port for communication with the chamber, means to prevent effective resistance to the operative movement of the piston, and a tubular cutter carried by the piston and having a port in registration with the port in the piston extension and adapted to cut the central portion of the disk in its forward movement with the piston.

35 27. In combination, a container carrying fluid under pressure, a member secured to the container and formed with a seat and an outlet opening, a closure disk, means retaining the disk on the seat to close the opening, a second member for connection with the first-mentioned member and adapted to fit against the first-mentioned member and forming a chamber and having an outlet opening, a piston in the chamber, a cutter carried by the piston to open the disk, and a coupling part carried by one member and threaded to the other member detachably connecting the members.

40 28. In combination, a container for carrying fluid under pressure, a device connected with the container and having an outlet opening, a penetrable closure for said opening, a body connected with said device and having a chamber, a piston operable in the chamber, a cutter carried by the piston and slidably fitting said opening, the cutter being operable to open the closure.

45 29. In combination, a container for carrying fluid under pressure, a device connected with the container and having an outlet opening, a penetrable closure for said opening, a body connected with said device and having a chamber, a piston operable in the chamber, a cutter carried by the piston, the cutter being operable to open the closure, there being a passage through the cutter and piston through which fluid from the container passes to the chamber to act on one side only of the piston.

50 30. In an apparatus of the character described,

a container for fluid under pressure having a discharge port, a closure for said port yieldable under abnormal pressure, opening means operable at will to open said closure and discharge fluid from the container, a conduit constituting the sole means for delivering the discharged fluid to a desired point, and safety means preventing delivery of fluid from the container to said point unless said opening means is operated.

5 31. In an apparatus of the character described, a primary and secondary container for fluid under pressure, each container having a discharge port and a closure member therefor, the closure member of the primary container comprising a frangible disk yieldable to abnormal fluid pressure, a primary opening means operable at will to open the closure member of the primary container to discharge fluid therefrom, a secondary opening means operable by fluid pressure for opening the closure member of the secondary container, a conduit constituting the sole means for leading fluid discharged by the primary opening means to operate the secondary opening means, and safety means preventing delivery of fluid to operate the secondary opening means unless said primary opening means is operated.

10 32. In combination, a container having a discharge port, a frangible closure member for said port adapted to retain fluid under pressure in the container but yieldable under pressure above a predetermined value, means operable at will for rupturing said member to release fluid from the container, a conduit for delivering the fluid thus released to a predetermined point at which it is not desirable to have an accidental discharge, a pressure relief port for the container leading to another point, and a frangible closure member controlling the pressure relief port, the latter member being adapted to yield at a lower pressure than that at which the first member would yield so as to prevent accidental release of fluid from the container into the conduit by a rise of pressure in the container.

15 33. In combination, a container carrying a fluid under pressure, a penetrable closure member for the container, a punch adapted to penetrate the closure member and cut a flap out of said member but integrally attached thereto at one side, said punch being tubular in form and provided with a sharp cutting edge and with a blunt shoulder at one side adapted to engage the closure member and form an anvil about which the attached side of the flap may be bent by pressure of the fluid, and means for operating the punch.

20 34. In combination, a container carrying a fluid under pressure, a penetrable closure member for the container, a punch adapted to penetrate the closure member and cut a flap out of said member but integrally attached thereto at one side, said punch being tubular in form and provided with a sharp cutting edge and with a blunt shoulder at one side adapted to engage the closure member and form an anvil about which the attached side of the flap may be bent by pressure of the fluid, means for operating the punch, and means for limiting the penetrating movement of the punch.

25 35. In combination, a container carrying fluid under pressure, a penetrable closure member for the container, a punch adapted to penetrate the closure member and cut a flap out of said member but integrally attached thereto at one side, said punch being tubular in form and provided with a sharp cutting edge and with a blunt shoulder at one side adapted to engage the closure member

and form an anvil about which the attached side of the flap may be bent by pressure of the fluid, said cutting edge being sharpened inwardly toward the inner periphery of the punch so that said edge will be substantially coincident with said inner periphery, and means for operating the punch.

36. A releasing device for a container holding fluid under pressure and having an outlet with a penetrable closure member normally sealing said outlet, said device comprising a hollow body having a discharge port, a tubular punch operable in the body to puncture and cut a flap out of said member, the cutting end of the punch being slanted with respect to the longitudinal axis of the punch and being sharpened toward the inner periphery of said punch to form an arcuate cutting edge substantially coincident with said inner periphery and lying in a plane inclined from normal to said axis, whereby in operation the cutting edge will penetrate the closure member initially at one point and the cut will then be developed circularly with a shearing action in opposite directions from said point, means for operating the punch, and means for arresting the punch after a flap has been cut of more than 180 degrees in extent but sufficiently less than 360 degrees to leave an integral connection between the flap and the body of the member on which the flap will be hinged by the pressure of said fluid without tearing off.

37. A releasing device for a container holding fluid under pressure and having an outlet with a penetrable closure member normally sealing said outlet, said device comprising a hollow body having a discharge port, and a tubular punch operable in the body to puncture and cut a flap out of said member, the cutting end of the punch being slanted with respect to the longitudinal axis of the punch and being sharpened toward the inner periphery of said punch to form an arcuate cutting edge substantially coincident with said inner periphery and lying in a plane inclined from normal to said axis, whereby in operation the cutting edge will penetrate the closure member initially at one point and the cut will then be developed circularly with a shearing action in opposite direction from said point, the cutter being formed with a recess interrupting the cutting edge on the side opposite said point to leave a hinge portion integrally connecting the cut-out flap and the body of the member, said recess being not more than 180 degrees in extent but having a minimum extent sufficient to provide a hinge on which the flap may be bent by the pressure of said fluid without tearing off.

38. A releasing device for a container holding fluid under pressure and having an outlet with a penetrable closure member normally sealing said outlet, said device comprising a hollow body having a discharge port, a tubular punch operable in the body to puncture and cut a flap out of said member, the cutting end of the punch being slanted with respect to the longitudinal axis of the punch and being sharpened toward the inner periphery of said punch to form an arcuate cutting edge substantially coincident with said inner periphery and lying in a plane inclined from normal to said

axis, whereby in operation the cutting edge will penetrate the closure member initially at one point and the cut will then be developed circularly with a shearing action in opposite direction from said point, the cutter being formed with a recess interrupting the cutting edge on the side opposite said point to leave a hinge portion integrally connecting the cut-out flap and the body of the member, said recess being not more than 180 degrees in extent but having a minimum extent sufficient to provide a hinge on which the flap may be bent by the pressure of said fluid without tearing off, means for operating the punch, and means for arresting the punch when a cut equal in extent to the entire cutting edge has been made in said member.

39. A releasing device for a container holding fluid under pressure and having an outlet with a penetrable closure member normally sealing said outlet, said device comprising a hollow body having a discharge port, a tubular punch operable in the body to puncture and cut a flap out of said member, the punch being sharpened toward the inner periphery of said punch to form an arcuate cutting edge, said cutting edge being inclined with respect to a plane normal to said axis, whereby in operation the cutting edge will penetrate the closure member initially at one point and the cut will then be developed circularly with a shearing action from said point, means for operating the punch, and means for arresting the punch after a flap has been cut of more than 180 degrees in extent but sufficiently less than 360 degrees to leave an integral connection between the flap and the body of the member on which the flap will be hinged by the pressure of said fluid without tearing off.

40. In combination, a container carrying fluid under pressure, a penetrable closure member for the container, a tubular punch adapted to penetrate the closure member and cut a flap out of said member, the cutting end of said punch being sharpened inwardly toward the inner periphery of the punch so as to make a cut in the closure member of smaller diameter than the outside diameter of the punch, the cutting end of the punch being recessed to provide a blunt shoulder of substantial extent between opposite ends of the cutting edge, means for advancing the punch so that the cutting edge will penetrate the closure member, and a stop for limiting advance of the punch to prevent said shoulder from being forced through the closure member.

41. A container for fluid under pressure having a discharge port, a sealing disk normally closing the port but being rupturable at will to release said fluid, the container also having a safety port, and a safety disk normally closing the safety port, both of the disks being rupturable by an abnormal rise of pressure of the fluid, the discharge port being of such size that upon rupture of said sealing disk the fluid escaping therefrom may produce an undesirable recoil, the safety port being of such smaller diameter than the discharge port that the recoil resulting from fluid escaping from the safety port will be maintained within desirable safety limits.
